BUILDING WALL

George V. R. Dunan, Miami, Fla., assignor to Dunan
Brick Yards, Incorporated, Miami, Fla., a corporation of Florida

Filed Oct. 25, 1960, Ser. No. 62,612

Term of patent 14 years

(Cl. D18—2)

Fig. 1.

Fig. 3.

Fig. 2.

Fig. 4.

Fig. 5.

I claim:

The ornamental design for a building wall, substantially as shown.
